CLOCK

Filed March 11, 1931

Inventor:

Abram J. Schuler;

By: Arthur W. Schuler

Atty.

UNITED STATES PATENT OFFICE

ABRAM J. SCHULER, OF CHICAGO, ILLINOIS

DESIGN FOR A CLOCK

Application filed March 11, 1931. Serial No. 39,033. Term of patent 14 years.

To all whom it may concern:

Be it known that I, ABRAM J. SCHULER, a citizen of the United States, and a resident of Chicago, county of Cook, and State of Illinois, have invented a new, original, and ornamental Design for a Clock, of which the following is a specification, reference being had to the accompanying drawing, forming a part thereof, in which the figure is a perspective view of a clock, showing my new design.

I claim:

The ornamental design for a clock substantially as shown.

ABRAM J. SCHULER.
